UNITED STATES PATENT OFFICE.

GEORGE SLIDER, OF BALTIMORE, MARYLAND.

GEARING.

Application filed November 18, 1921. Serial No. 516,007.

To all whom it may concern:

Be it known that I, GEORGE SLIDER, a citizen of the United States, residing at Baltimore, in the State of Maryland, have invented certain new and useful Improvements in Gearing; and I do hereby declare the following to be a full, clear, and exact description of the invention, such as will enable others skilled in the art to which it appertains to make and use the same.

My invention relates to gearing.

Among the objects of my invention are:— To produce gearing such as is suitable for driving the pinte of one of a pair of rolls such as are used in wringers forming a part of a washing machine.

To produce gearing suitable for rotating a pinte at will in either direction.

To produce gearing for rotating a pinte at will in either direction and combining said gearing with indexing mechanism whereby the position in space of said pinte may be varied as desired.

These and other objects of my invention will become apparent in the following specification reference being had to the accompanying drawings, and the means by which said objects are effectuated will be definitely pointed out in the claims.

In the drawings:—

Figure 1 is a vertical elevation partly in section of my improved gearing.

Fig. 2 is a section along the line 2—2 in Fig. 1 looking in the direction of the arrows.

Fig. 3 is an enlarged section along the line 3—3 in Fig. 2 looking in the direction of the arrows.

Fig. 4 is a section along the line 4—4 in Fig. 1 looking in the direction of the arrows.

In the drawings:—

16 represents the pinte of one roll of the wringer of a washing machine which has sides such as 22 forming a hollow truss which supports the housings, the remaining pinte of said roll and the pintles of the other roll. The sides such as 22 are secured to the casting 27 by bolts such as 26 and 28.

With the exception of the pinte 16 and casting 27 all of the parts hereinbefore mentioned formed no part of my present invention. They may be of any usual or preferred construction.

The casting 27 is provided with a cap 10 closing the right hand end thereof and se-

cured thereto by bolts such as 11. The cap 10 and casting 27 are provided with housings 12 and 13, respectively, for the pinte 16, and bevel gears 14 and 15 are revolvably mounted upon said shaft adjacent said housings 12 and 13, respectively.

The extremities of a squared portion 17 on the pinte 16 serve, in conjunction with the faces of the housings 12 and 13, to prevent undue end play of the gears 14 and 15. The gears 14 and 15 are provided with clutch members 18 and 19, respectively, and a cooperating clutch member 20 is slidably mounted upon the squared portion 17. The member 20 is provided with clutch teeth 21—21 and 23—23 which alternately engage with the clutch members 18 and 19, respectively, in order to revolve the pinte 16 in either direction. The member 20 is provided with a groove into which the shifting pin 24 projects, said pin being provided with a cylindrical portion which is revolvably mounted in a bearing provided in the shifting lever 25. The shifting lever 25 is rigidly attached to the shifting shaft 29 and the latter is operated by the shifting handle 30. The lever 25 is provided with a notch 31 and with beveled faces 32 and 33 which co-act with a point formed on the face of the clutch detent 34 in order to hold the clutch member 20 in either the neutral or either one of the driving positions.

The detent 34 is slidably mounted in a boss formed on the inside of the casting 27 and is pressed against the lever 25 by the spring 35.

The gears 14 and 15 mesh with the bevel gear 36, the latter being rigidly secured upon the upper end of the driving shaft 37 and revolving in the direction of the arrow shown in Fig. 1 which drives said gears in the directions of the arrows shown in said figure.

The shaft 37 is revolvably mounted in the housings 38 and 39 provided in the index arbor 40 and the latter is secured to the casting 27 by bolts such as 41.

The arbor 40 is provided with cylindrical portions which are revolvably mounted in the bearings 42 and 43 provided in the index sleeve 44 and the latter is secured by bolts such as 45 to the framework 46 of the washing machine. The arbor 40 is provided with a plurality of index holes such as 47 of which there may be any desired number suitably located.

The index pin 48 is slidably mounted in the boss 49 and is normally pressed into engagement with one of the holes 47 by the spring 50, an index handle 51 serving to remove said pin from engagement with one of the holes 47 when desired.

The pins 48 and holes 47 are made tapering so that the pressure of the spring 50 will prevent relative movement of the arbor 40 in the sleeve 44.

The operation of my improved gearing is as follows:—

The handle 30 being in the position shown in Figs. 1, and 2, the lever 25 and the member 20 will be in the position shown in Fig. 3 and the clutch teeth 21—21 and 23—23 will be disengaged from the clutch members 18 and 19. When the handle 30 is in said position and the shaft 37 is revolved in the direction of the arrow in Fig. 1, the gears 14 and 15 will be revolved in the direction of the arrows in said figure, but no rotation of the pintle 16 will result.

It is to be noted that the handle 30 is yieldably held in the positions shown in Figs. 1 and 2 by the engagement of the detent 34 in the notch 31 in the lever 25.

If it is desired to rotate the shaft in the same direction of the gear 14, the handle 30 is to be removed from the position shown in Figs. 1 and 2 and represented by the dotted line 52 in Fig. 3 to the position represented by the dotted line 53 in said figure, thus bringing the teeth 21 into engagement with the clutch member 18. When the handle is in said position, the face 33 of the lever 25 will be engaged by the detent 31 and the teeth 21—21 will be held in engagement with the member 18.

When it is desired to revolve the pintle 16 in the opposite direction the handle 30 is to be moved from the position represented by the dotted line 53 in Fig. 3 to the position represented by the dotted line 54 in said figure, thus bringing the teeth 23—23 into engagement with the member 17. When the handle is in said position, the face 32 of the lever 25 will be engaged by the detent 31 and the teeth 23—23 will be held in engagement with the member 19.

When it is desired to change the angular position of the pintle 16 with reference to the index sleeve 44, the operator pulls the handle 51 outwardly, thus removing the pin 48 from the corresponding index hole 47.

The casting 27 can then be turned to any desired position and when the handle 51 is released the pin 48 will enter the corresponding index hole and lock said casting in position.

Thus, it will be seen that I provide a simple, cheap and effective combination for driving wringer rolls in either direction or for terminating their rotation at will, and also for holding the wringer in any angular

position with reference to the device by which it is supported.

While I have shown one preferred embodiment of my invention and one use for which the same is adapted, yet it is to be understood that unless specifically claimed, I do not desire to be limited to the construction shown, nor to the specific application thereof, for many changes may be made in the construction of my improved gearing and it may be applied for a wide variety of uses without departing from the spirit of my invention.

I claim:

1. The combination with an arbor, a driving shaft revolubly mounted therein, a gear fixed on said shaft, and a casting open at one end and having its bottom secured to said arbor, said casting having an opening in said bottom to permit the passage of said gear therethrough, of a cap secured to said casting for closing said end, a housing in each of said casting and cap, a pintle revolubly mounted in said housings, a gear revolubly mounted on said pintle adjacent each housing and meshing with said first named gear, a squared portion on said pintle between said gears forming a shoulder for said gears, a clutch member on each gear, a cooperating clutch member slidably mounted on said portion, and means for moving said cooperating clutch member.

2. The combination with an arbor, a driving shaft revolubly mounted therein, a gear fixed on said shaft, and a casting open at one end and having its bottom secured to said arbor, said casting having an opening in said bottom to permit the passage of said gear therethrough, of a cap secured to said casting for closing said end, a housing in each of said casting and cap, a pintle revolubly mounted in said housings, a gear revolubly mounted on said pintle adjacent each housing and meshing with said first named gear, a squared portion on said pintle between said gears forming a shoulder for said gears, a clutch member on each gear, a cooperating clutch member slidably mounted on said portion, a lever for moving said cooperating clutch member, notches in said lever and a detent engaging said notches for holding said cooperating clutch member in engagement with either of said second named gears or in disengagement from both.

3. The combination with an arbor, a driving shaft revolubly mounted therein, a gear fixed on said shaft, and a casting open at one end and having its bottom secured to said arbor, said casting having an opening in said bottom to permit the passage of said gear therethrough, of a cap secured to said casting for closing said end, a housing in each of said casting and cap, a pintle revolubly mounted in said housings, a gear

revolvably mounted on said pintle adjacent each housing and meshing with said first named gear, a squared portion on said pintle between said gears forming a shoulder for said gears, a clutch member on each gear, a cooperating clutch member slidably mounted on said portion, a shifting shaft revolvably mounted in said casting, a handle and a lever secured to said shaft, a groove in said cooperating clutch member, and a pin revolvably mounted in said lever and extending into said groove.

In testimony whereof, I affix my signature.

GEORGE SLIDER.
